(57) CLAIM

The ornamental design for a ring toss game, as shown and described.

DESCRIPTION

FIG. 1 is a top, front, right side perspective view of a ring toss game in an unfolded configuration in accordance with the present invention;

FIG. 2 is a left side view thereof;

FIG. 3 is a right side view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a top, front, right side perspective view of the ring toss game in a folded configuration in accordance with the present invention;

FIG. 9 is a left side view thereof;

FIG. 10 is a right side view thereof;

FIG. 11 is a top plan view thereof;

FIG. 12 is a bottom plan view thereof;

FIG. 13 is a front elevation view thereof; and,

FIG. 14 is a rear elevation view thereof.

The broken lines in the drawings depict portions of the ring toss game that form no part of the claimed design.
